UNITED STATES PATENT OFFICE

159,254

COMBINED STRAIGHT EDGE AND LEVEL

Antoine S. Daudelin, Essex Junction, Vt.

Application November 10, 1949, Serial No. 5,983

Term of patent 3½ years

(Cl. D52—1)

To all whom it may concern:

Be it known that I, Antoine S. Daudelin, a subject of the King of Great Britain, residing at Essex Junction, in the county of Chittenden and State of Vermont, have invented a new, original, and ornamental Design for a Combined Straight Edge and Level, of which the following is a specification, reference being had to the accompanying drawing, forming part thereof.

Figure 1 is a top plan view of a combined straight edge and level, showing my new design;

Figure 2 is a side elevational view thereof;

Figure 3 is an end elevational view thereof taken on the line 3—3 of Figure 2 looking in the direction of the arrows, and

Figure 4 is a cross-sectional view of the same taken substantially on the plane of the line 4—4 of Figure 2, looking in the direction of the arrows.

I claim:

The ornamental design for a combined straight edge and level, as shown.

ANTOINE S. DAUDELIN.
